UNITED STATES PATENT OFFICE.

JOHN T. ARNOLD, OF HICKSVILLE, OHIO.

DESIGN FOR A WASH-BOARD.

SPECIFICATION forming part of Design No. 16,537, dated February 23, 1886.

Application filed November 28, 1885. Serial No. 184,326. Term of patent 7 years.

To all whom it may concern:

Be it known that I, JOHN T. ARNOLD, of Hicksville, in the county of Defiance and State of Ohio, have invented and produced a new 5 and original Design for a Wash-Board, of which the following is a full, clear, and exact description.

My design for a wash-board consists in a novel configuration of the facial surfaces of 10 the crimp, the same giving to the whole, when viewed from a distance, a step-like and checkered appearance, as hereinafter described.

Reference is to be had to the accompanying drawings, forming part of this specification, 15 and in which—

Figures 1 and 2 are views in perspective of my newly-designed wash-board crimp from its opposite sides or faces, and reversed end for end.

20 A A' indicate the two or opposite sides or faces of the crimp. The face A shows a series of inverted parallel steps or step-surfaces, b b, extending across the crimp, the "treads" of the steps being set inclining 25 relatively to the "rises" thereof, so that the several steps lie in the same general plane. Said steps or step-surfaces are crossed by a series of parallel ridges, c c, the same being at

right angles to the lengths of the steps, and of an approximataly convex shape in transverse section, they being made shelving from opposite sides. These ridges are at such distances apart as to give to the whole surface A of the crimp a step-like and checkered appearance. The opposite side or surface, A', of 35 the crimp also presents an inverted-step and checkered appearance, and when the crimp is turned end for end shows a series of parallel inverted steps, b b, having inclined treads, and extending across the crimp; but, instead 40 of a series of ridges crossing the steps, there are a series of parallel grooves, c' c', so arranged, said grooves being of approximately concave shape in transverse section.

I claim—

45 The design for a wash-board herein shown and described, the same consisting of a crimp having a series of parallel step-like surfaces, b, having a series of parallel ridges, c and c', across them of approximately convex form 50 upon the one face and concave form upon the other face in transverse section.

JOHN T. ARNOLD.
